CLIFFORD F. MUTH, OF CINCINNATI, OHIO

MACHINE FOR AND METHOD OF EMBEDDING REINFORCING WIRE IN WAX
BEEHIVE FOUNDATIONS

Application filed April 25, 1930. Serial No. 447,261.

Instead of first clamping wax foundation sheets in the usual frames and then wiring them to prevent warping and sagging, pre-wired foundation sheets are now available for mounting in the frames with much more ease and less expenditure of time, and it is the principal object of my invention to provide a novel machine for embedding the reinforcing wire in the foundation sheets, in an expeditious manner.

Another object of the invention is to provide a novel method of embedding the reinforcing wire in the sheets, whether such method be carried out by the machine herein disclosed, or otherwise.

With the foregoing in view, the invention resides in the novel subject matter herein-after described and claimed, description being accomplished by reference to the accompanying drawings.

Fig. 1 is a top plan view partly broken away and in horizontal section, showing the machine constructed in accordance with my invention.

Fig. 2 is a side elevation partly broken away.

Fig. 3 is a view similar to Fig. 2 but looking at the opposite side of the machine.

Figs. 4, 5 and 6 are vertical sectional views on lines 4—4, 5—5 and 6—6 of Fig. 1.

Fig. 7 is a fragmentary top plan view showing a slight modification.

The drawings above briefly described, illustrate the preferred construction and while such construction will be herein specifically explained, it is to be understood that within the scope of the invention as claimed, numerous variations may be made.

The numerals 8 denote legs supporting longitudinal bars 9 upon which a table top 11 is mounted, said table top embodying a platen portion 12 and a gap 13 at one transverse edge of said portion 12. Mounted in this gap for movement longitudinally of the table 11, is a bar 14 which is provided with a plurality of rigid hooks 15. Similar hooks 16 are secured to the table 11 near the opposite edge of the platen portion 12 and both edges of this portion are provided with upstanding ridges 17 which extend transversely of

the table, said ridges being preferably formed from insulating rods inlaid in the platen portion 12. Secured to the table 11 at opposite ends of the row of hooks 16, are two clamps 18 and 19, the latter embodying a suitable wire cutter 20. Under the clamp 19, suitable provision 21 is made for supporting a reel 22 of fine wire 23. It is intended that a length of this wire shall be unreeled after passage through the wire guide 24 and shall have its free end secured by the clamp 18. The reach of wire is then "zig-zagged" over the platen 12, the bight portions 25 at the ends of the wire reaches 26, being engaged with the hooks 15 and 16, and said reaches being disposed upon the ridges 17. The wire is then held by the clamp 19 and the bar 14 is shifted outwardly to stretch the reaches of wire, the bar 14 being outwardly moved and held by means hereinafter described. After so stretching the wire reaches, an electric current is passed through the zig-zag length of wire to heat it, so that by placing a wax foundation sheet S upon the heated wire reaches, and depressing said sheet, the wires will melt their way into the sheet, finally becoming embedded therein as indicated in Figs. 4 and 5. The provision for directing current through the wire for a proper interval of time, will be hereinafter described.

After embedding of the wire reaches in the foundation sheet S, bar 14 is inwardly moved and the bight portions 25 of the reinforcement are removed from the hooks 15 and 16, allowing lifting of the reinforced foundation sheet from the platen 12. Then, the bight portions 25 are preferably trimmed off along opposite edges of the sheet, and this trimming may be effected by a suitable shear 27 mounted at one end of the table 11.

The ends of the bar 14 are mounted in appropriate guides 28 and the lower side of said bar is provided with two racks 29 meshing with pinions 30 on a transverse shaft 31 supported in bearings carried by the bars 9. On one end of shaft 31, is a large sprocket wheel 32 which is connected by a chain 33 with a small sprocket 34 on another transverse shaft 35. The shaft 35 is provided with ap-

propriate means 36 whereby it may be rotated, thereby forcibly driving the shaft 31 for the purpose of causing the pinions 30 and racks 29 to move the bar 14 outwardly to stretch the wire reaches 26. The end of shaft 31 remote from sprocket 32, is provided with a ratchet wheel 37 co-operable with a spring-applied dog 38 for holding the shaft against retrograde movement when bar 14 has been moved outwardly to the desired extent. Turning of shaft 31 in a direction to stretch the wire reaches 26, tensions a spring 39 (Figs. 1 and 4) wrapping it partially about the hub of the sprocket 32, so that this spring may later be relied upon to turn shaft 31 in a direction to move bar 14 inwardly. A foot pedal 40 is connected by a wire or the like 41 with the dog 38 for releasing the latter when desired. Hence, as soon as the wire reaches 26 have been embedded in a foundation sheet, depression of the foot pedal 40 will release the dog 38 and spring 39 will function to inwardly move bar 14. Hence, upon operation of the cutter 20 to sever the zig-zag length of wire from the remainder of the latter, the bight portions of said zig-zag length may be removed from the hooks 15 and 16, it being also of course necessary to release the clamp 18.

Current-conducting wires 41 and 42 are shown connected with the wire clamps 18 and 19 respectively, said conductors leading from a time switch 43 to which conductors 44 extend from a transformer 45 lead wires to said transformer being shown at 46. When the time switch 43 is closed, current travels through the various wire reaches 26, heating them to the required extent to allow them to melt their way into a wax foundation sheet, and when they have been thus properly heated, the time switch again opens the circuit so that extensive melting of the sheet cannot take place.

For depressing any sheet S after it has been placed upon the tight wire reaches 26, I provide a suitable pressing member 47 which is hinged at 48 and provided with a suitable handle 49, a spring 50 being employed to hold said member 47 normally raised and to assist in again raising said member after it has been lowered.

By preference, the number 47 embodies a glass plate 51 having a covering 52 of sponge rubber, said covering being adapted to contact with the foundation sheet S and to press against the latter without any danger of injuring it.

In operation of the machine, a length of wire is unreeled from the reel 22, is clamped by the clamp 18, is zig-zag into engagement with the hooks 15 and 16, and is fastened by the clamp 19. Then, the handle 36 is operated to effect outward movement of bar 14, causing tight stretching of the wire reaches 26 and holding of them snugly upon the ridges 17.

Now, a foundation sheet S is laid upon the reaches 26, the time switch 43 is closed and the pressing member 47 is lowered, the result being that the current flow through the zig-zag length of wire, warms the latter, causing its reaches 26 to melt their way into the wax sheet S and causing the wax to run around said reaches to anchor them. When the wire has reached the necessary temperature, the time switch 43 again opens the circuit so that excessive melting of the wax cannot take place. Now, by depressing pedal 40, dog 38 is released and spring 39 will inwardly move the bar 14. Wire cutter 20 is then operated and the wire clamping means 18 is loosened, whereupon the wired foundation sheet may be disengaged from the machine. Now, the bight portions 25 of the reenforcement and the free ends of the wire are preferably trimmed off by the shear 27. When clamp 19 is now loosened, another reach of the wire 23 may be unreeled for positioning in the same manner as above described.

It will be noted on reference to Fig. 4 that the glass rods or other insulating ridges 17 have their upper surfaces disposed above the surface of the platen a distance corresponding to one-half of the thickness of the sheet of foundation and when the wires are heated and the pressing member 47 moved downwardly, the sheet of foundation will be forced against the wires until its bottom surface rests on the platen, the cushioning face 52 of the pressing member preventing injury to the upper surface of the foundation. The time controlled switch is of course set to heat the wires to the proper degree. In practice, I have obtained satisfactory results by setting down the usual 110 volt current to 25 volts and setting the time controlled switch to maintain the current for about five seconds, but of course the strength of the current and time interval may be varied.

Attention is invited to the fact that the reaches 26 may extend in any desired direction. In Fig. 1, the arrangement of the hooks 15 and 16 is such that said reaches are all oblique to the length of the foundation sheet, whereas in Fig. 7 showing a different arrangement of the hooks, the reaches 26 will all be at about right angles to the length of said sheet.

Insofar as I am advised, I am the first to heat the wire reenforcement by passing an electric current through it, then relatively moving the reenforcement and foundation sheet to cause the former to melt its way into the latter. While the machine herein disclosed is preferably used for carrying out this method, it will be obvious that it could be effected in other ways. Moreover, it will be clear that the construction of the machine could be changed materially and still obtain the necessary functions. Hence, it is to be understood that the present disclosure is pri-

marily for illustrative purposes and that the invention as claimed comprehends numerous variations.

What is claimed is:

- 5 1. A machine for embedding reenforcing wire in beehive comb foundations, comprising means for holding a plurality of reaches of wire in stretched condition, means for heating the reaches whereby said reaches will melt their way into a comb foundation when the latter is placed against said reaches.
- 10 10. their way into a comb foundation when the latter is placed against the reaches, means for relatively moving said comb foundation and the heated wire reaches to expedite embedding of the latter in the former, and means for limiting the relative movement of said comb foundation and reaches to prevent passage of the latter entirely through the comb foundation.
- 15 11. A machine for embedding reenforcing wire in beehive comb foundations, comprising two relatively movable supports, one of said supports having means for holding one end of a plurality of wire reaches, the other of said supports having means for holding the other ends of said reaches, means for relatively moving said supports to stretch said reaches, and means for heating said reaches, whereby they will melt their way into a comb foundation when the latter is placed against the reaches.
- 20 12. A machine for embedding reenforcing wire in beehive comb foundations, comprising two relatively movable supports, one of said supports having hooks for holding alternate bight portions of a zig-zag wire length, the other of said supports having hooks for holding the intervening bight portions of the zig-zag wire length, securing means for the ends of said wire lengths, means for relatively moving said supports to stretch the reaches of wire, and means for heating the reaches whereby said reaches will melt their way into a comb foundation when the latter is placed against the former.
- 25 13. 4. A machine for embedding reenforcing wire in wax beehive comb foundations, comprising means for holding a plurality of reaches of wire in stretched condition, electrical conducting means adapted for connection with the wire to heat the reaches thereof, allowing said reaches to melt their way into a comb foundation when the latter is placed against the former, means for relatively moving the comb foundation and the heated wire reaches to expedite embedding of the latter in the former, and means for limiting the relative movement of said comb foundation and reaches to prevent passage of the latter entirely through the comb foundation.
- 30 14. 5. A machine for embedding reenforcing wire in beehive comb foundations, comprising two relatively movable supports, one of said supports having hooks for holding alternate bight portions of a zig-zag wire length,

the intervening bight portions of said zig-zag wire length, means for holding the ends of the wire length, means for relatively moving said supports to stretch the wire reaches, and electrical conducting means for placing the wire length in an electric circuit to heat said reaches, whereby said reaches will melt their way into a comb foundation when the latter is placed against said reaches.

6. A machine for embedding reenforcing wire in wax beehive comb foundations, comprising a table embodying a platen having ridges along two opposite edges, a row of hooks spaced horizontally outward from one of said ridges, a bar mounted for horizontal movement toward and from the other ridge and having a row of hooks, said rows of hooks being adapted to engage the bight portions of a zig-zag length of wire with its reaches lying upon said ridges, clamps for holding the ends of the wire length, means for moving said bar to stretch said reaches, conducting means connected with said clamps for placing the wire length in an electric circuit to heat the wire, and a pressing member hinged to the table for pressing a wax comb foundation against the heated wire onto the platen.

7. In a machine of the character set forth, a table including a platen, two rows of hooks associated with the platen, a slideable bar on one side of the table carrying one of said rows of hooks, a string-actuated, rotatable shaft mounted on the table, manually actuated means for rotating the shaft to place its actuating spring under tension, pawl and ratchet means for holding the shaft with its actuating spring under tension, manually actuated means for releasing the pawl and ratchet means, and means actuated by said shaft for sliding said bar.

8. In a machine of the character set forth, a platen, means for attaching and holding a zig-zag length of wire with its reaches spaced a predetermined distance above the platen, a pressing member to press a comb foundation sheet against said wire and platen, and a cushioning surface on said pressing member to engage the comb foundation sheet.

9. In a machine of the character set forth, a table including a platen, a row of hooks along one side of said platen, a wire clamp at each end of said row of hooks, a wire cutter associated with one of said clamps, a tubular wire guide adjacent the last named clamp, means for supporting a spool of wire adjacent said tubular guide, a movable bar on the table adjacent said platen and carrying a second row of hooks, and means for moving and holding said bar to tension a length of wire held by said clamps with its intermediate portion engaged with the hooks of both rows and arranged in zig-zag form over the platen.

10. In a machine of the character set forth,

- a platen, spaced ridges associated therewith and having their upper edges spaced above the platen a distance corresponding substantially to one-half of the thickness of the comb foundation sheet, means for stretching and holding a zig-zag length of wire above the platen with its reaches supported on said ridges, and a pressing member for moving a sheet of comb foundation against said wire and platen. 5 70
11. In a machine of the character set forth, a platen, spaced ridges associated therewith and having their upper edges spaced above the platen a distance corresponding substantially to one-half of the thickness of the comb foundation sheet, means for stretching and holding a zig-zag length of wire above the platen with its reaches supported on said ridges, means for passing an electric current 15 75 through the wire to heat the same, and a pressing member for moving a sheet of comb foundation against said wire and platen. 20 80
12. In a machine of the character set forth, a platen, means for stretching and holding 25 85 a zig-zag wire with its reaches spaced a predetermined distance above the platen, an electric circuit including a time-controlled switch and conductors for electrical connection to the ends of said wire length, and a 30 90 pressing member for moving a sheet of comb foundation against said wire and platen. 35 95
13. The method of producing a wire reenforced beehive comb foundation, comprising the steps of stretching a wire in zig-zag form, 40 100 heating the wire, relatively moving the comb foundation and heated wire to cause the latter to melt its way into the former and trimming off the bight portions of the wire, thereby preparing the reenforced foundation for subsequent mounting in a frame. 45 105
14. A machine for embedding reenforcing wire in beehive comb foundations, comprising a table embodying a platen having ridges along two opposite edges, two rows of hooks 50 110 spaced horizontally outward from said ridges respectively, said rows of hooks being adapted to engage the bight portions of a zig-zag length of wire with its reaches lying upon said ridges, means for heating said wire reaches, 55 115 and means for relatively moving said two rows of hooks to tighten said wire reaches between said ridges. 60 120
15. In a machine of the character set forth, a table including a platen, two rows of hooks 65 125 associated with said platen, a slid able member mounted on the table and carrying one of said rows of hooks, a spring-actuated rotatable shaft mounted on the table, manually actuated means for rotating the shaft to place its actuating spring under tension, means for holding the shaft with its actuating spring under tension, said holding means being manually releasable, and means actuated by said shaft for moving said hook-carrying member. 70 130
16. In a machine of the character set forth,
